United States Patent Office

Des. 222,074
Patented Sept. 28, 1971

222,074

BIRD HOUSE

Charles D. Pratt, Box 264, Martinicus Island,
Maine 04851

Filed June 26, 1970, Ser. No. 23,691

Term of patent 14 years

Int. Cl. D30—02

U.S. Cl. D30—3

FIG. 1 is a perspective view of a bird house or similar article showing my new design;

FIG. 2 is a rear view thereof;

FIG. 3 is a front view thereof;

FIG. 4 is a side view thereof; and

FIG. 5 is a top plan view.

I claim:

The ornamental design for a bird house, substantially as shown.
